UNITED STATES PATENT OFFICE.

DAVID ADAM CHRISTIAN, OF LONDON, ENGLAND, ASSIGNOR TO SIEMENS BROTHERS & COMPANY, LIMITED, OF LONDON, ENGLAND, A BRITISH COMPANY.

AUTOMATIC AND SEMIAUTOMATIC TELEPHONE SYSTEM.

Application filed September 7, 1923. Serial No. 661,427.

To all whom it may concern:

Be it known that I, DAVID ADAM CHRISTIAN, a British subject, residing at London, England, have invented certain new and useful Improvements Relating to Automatic and Semiautomatic Telephone Systems, of which the following is a specification.

The present invention has reference to improvements in automatic telephone systems.

10 It has mainly in view arrangements for enabling a selector to successively hunt over more than one level to find a free or marked line. One case where such arrangements are desirable is that of a final selector where 15 lines to the same private branch exchange are situated in two or more adjacent levels and the final selector is to give access to a free line of the group leading to the private branch exchange.

20 The selector used in the present invention is provided with means for causing release as regards rotary motion only.

On reaching predetermined contacts in the first level unsuccessfully searched over, release as regards rotary motion takes place 25 and the selector wipers are then stepped up opposite to the next level and searching takes place over that level. If no free line is found there and lines of the group are provided in the next level, the process is 30 repeated. On reaching the last line of the group and it being found busy a busy signal may be given in the usual manner. The predetermined contacts referred to may be 35 extra contacts beyond the usual ten sets in a level, or may be the contacts immediately following the last contacts of the grouped lines situated in a level or some other suitable arrangement.

40 The accompanying diagrammatic drawing shows circuit arrangements according to the invention, for a selector having separate vertical and rotary release detents as shown in British patent specification No. 136,497, and 45 having an additional release magnet which operates solely on the rotary release detent.

Fig. 1 of the drawing shows circuit arrangements for a final selector having a group of P. B. X. lines assigned to the same 50 subscriber and occupying several levels of the selector.

Fig. 2 of the drawing shows circuit arrangements for a group selector, whereby, if 55 all the links outgoing from a given level are engaged, the selector wipers after traversing

the level, are released as regards the rotary movement and return to the position they occupied just before being stepped into the level and are then automatically stepped up opposite the next higher level and enter the 60 same.

Reference will now be had to Fig. 1 in which relays shown as having rectangles enclosing the windings are slow release relays. Two additional relays PS and PT are provided to assist in the carrying out of the invention. Furthermore the selector is provided with a double extra wiper having arms 10 and 11 of which 10 trails behind arm 11 so as to make contact with adjacent contacts 65 of contact arc 12. There is an arc of contacts 12 for each level containing P. B. X. lines and each contact of the arc corresponding to a P. B. X. line is connected to earth with the exception of the contact 70 corresponding to the last line of the group of P. B. X. lines.

A very convenient arrangement for the provision of contacts 12 is one in which a half cylinder of metal is fitted on the selector 80 above and in front of the ordinary bank of contacts. The half cylinder has one hundred tapped and drilled holes in which screws are inserted, as required, to form contacts 12. The holes are situated so as to correspond in 85 position with the bank contacts. The additional wipers are adapted to make contact with the said screws.

The vertical magnet is denoted by H, the rotary magnet by R, the main release magnet which withdraws both vertical and rotary release detents by M, and the rotary release magnet which acts only on the rotary release detent by M¹. Relay PR controls the circuit for the searching for a free P. B. X. 95 line. All contacts are shown in the unoperated position, contacts of relay A have a reference letter a followed by a suffix number and similarly for other relays; contacts which are operated by the wiper spindle on lifting from normal are denoted by the letter k and a suffix; contacts which operate when the wiper spindle rotates from normal position are indicated by the letter w and a suffix.

The circuit operations are as follows:— 100 When the final selector is seized, relay N is energized in a circuit from earth over battery, winding 1, contact k¹, test wire e and to ground over the test relay of the preceding selector. Relay N prepares a holding 110

circuit over its winding 2 and contact n^1 , which is shunted until contact h^1 opens on the first movement of the selector. Contacts n^2 , n^3 , and n^4 are closed or changed over in a manner obvious from the drawing.

The impulse relay A is energized, on the seizure of the selector, in a circuit from ground over contact pt^2 of relay PT, winding of relay A, back contact tr^3 of relay TR, back contact t^3 of test relay T, back contact s^3 of ring relay S, and over the b line to battery at the preceding selector.

Thereupon slow acting relay D is energized in a circuit from ground over battery, contact n^4 , winding of relay D, back contact pt^3 , front contact a^2 , off-normal contact h^3 , off-normal contact w^1 to earth. Relay D prepares the circuit of the vertical magnet H at front contact d^2 , and prepares a holding circuit for itself over contact d^3 , the initiating circuit being broken at contact h^3 , on the first movement of the wiper spindle. Relay D also at contact d^1 opens a point in a circuit for relay G. The subscriber operating his number dial causes relay A to beat and on each de-energization of relay A the vertical magnet H is energized in a circuit from earth over vertical magnet H, back contact g^2 of relay G, back contact a^1 , front contact d^2 to battery and earth. The selector wipers are stepped up to the required level and slow release relay D which is being held over its contact d^3 and the repeated closure of the circuit over back contact a^2 relapses on the termination of the train of impulses.

On the falling back of relay D, a circuit for relay G is closed, the circuit being from earth over battery, contact n^4 , winding of relay G which is slow acting, back contact pr^1 , back contact d^1 , back contact ps^3 , contact h^3 which changed over on the first vertical step, contact w^1 to earth. Relay G changes over, at its contact g^2 , the magnet operating circuit from the vertical to the rotary magnet and prepares a holding circuit for itself at front contact g^1 . It also closes a circuit for relay D at contact g^4 , the circuit being from earth, battery, closed contact n^4 , winding of relay D, back contact pt^3 , front contact a^2 , closed contact g^4 , contact w^1 to earth. Relay D energizes and completes the holding circuit for relay G at contact d^1 . Relay D, as before, prepares its own holding circuit at d^3 , and the magnet operating circuit at contact d^2 .

On receipt of the first of the train of impulses, relay A falls back and the rotary magnet R receives current from earth over battery, front contact d^2 , back contact a^1 , front contact g^2 , rotary magnet R to earth. The wipers are moved one step and contact w^1 opens leaving slow release relay D dependent for holding current on the circuit over the back contact a^2 . At the end of a

train of impulses, relay D releases since relay A is held energized. Relay D on release, breaks the holding circuit of relay G which falls back slowly. On the release of relay D the line called, is tested over the following circuit:—earth, battery, back contact d^2 of relay D, closed contact g^3 , windings 1 and 2 of relay T, closed contact n^3 , C arm of the final selector and over the test contact and wire to the called line. If the called line is free relay T energizes and closes a holding circuit for itself over contact t^1 and its low resistance winding 2. Relay G by this time falls back and opens the initial testing circuit at contact g^3 . Relay T at front contacts t^2 and t^3 connects the a and b speaking leads through to the a and b wipers of the selector. Relay G having fallen back a circuit is then made at contact g^1 for the ring relay S, the circuit being from earth over battery, winding of relay S, back contact a^3 (relay A de-energizes on the change over of contact t^3), back contact tr^1 , back contact ps^1 , contact w^2 in its off-normal position, contact g^1 to earth. Relay S energizes and interrupted ringing current from leads 13 and 14 is fed into the line to the subscriber's instrument over front contacts s^2 and s^3 . Winding 1 of the ring trip relay TR is in series with the lead 14. On the reply of the called subscriber relay TR is energized by direct current over the subscriber's loop, and at its front contact tr^1 , short circuits relay S and brings in the holding winding 2 of relay TR by opening the short circuit across it into the previously described circuit for relay S. Relay S de-energizing closes over its back contacts s^2 and s^3 the circuit through from the calling to the called subscriber. The release magnet circuit of the selector is kept open at contacts n^2 and t^1 . The holding circuit of relay T is controlled by relay N at contact n^3 , and on the termination of the call by the calling subscriber hanging up his receiver results in the de-energization of relay N with the consequent release of the final selector.

The sequence of operations described would apply in the case of an ordinary line or the first line of a P. B. X. group if free.

In the case of a busy ordinary line relay T would not operate so that relay A remains connected to the B lead over back contact t^2 . On the falling back of relay G a circuit is made for winding 2 of relay TR as follows; earth, contact g^1 , contact w^2 , back contact ps^1 , winding 2 of relay TR, front contact a^3 (which short circuits relay S), resistance, to battery. Relay TR energizes and connects a busy tone circuit over wires 15 and 16 and contacts tr^2 and tr^3 to the calling subscriber.

If the first line of the P. B. X. group were not free, the following sequence of operations would occur. Relay T does not ener-

- size on the fall back of contact d^2 so that relay PR has time to energize in a circuit from earth over battery, back contact t^1 , front contact n^2 , closed contact d^4 of relay 5 D, resistance, wiper 11 and the earthed contact of arc 12. Relay PR energizing opens contact pr^3 and thereby prevents a short circuit of its winding when on the next step wiper arm 10 reached the first earthed contact 10 tact of arc 12 which corresponds to the first B. P. X. line. Relay PR also at contact pr^2 closes a circuit from earth over battery, interrupter 15, contact pr^2 , front contact a^1 , front contact g^2 , rotary magnet R to earth; 15 relay G being held against release on the falling back of contact d^1 by the change over of contact pr^1 . The rotary magnet consequently steps the wipers round over the P. B. X. lines, relay T testing each line over 20 the circuit from earth, battery, back contact d^2 , closed contact d^3 , windings 1 and 2 of relay T, closed contact n^3 to the test wiper C. On a free line being found relay T operates, and at contact t^1 , opens the circuit of 25 relay PR. Relay PR relapsing opens the rotary magnet circuit at contact pr^2 . The ringing and other operations proceed as before.
- If all the P. B. X. lines on the level be 30 engaged, the means for releasing the selector in a rotary direction and the stepping up to the next level come into operation. These means include in the present case, relays PT and PS with the necessary circuits. 35 The provision of the additional wiper 10 and the short circuiting contact pr^3 of relay PR is to meet the case where it is required that a line of the P. B. X. group shall be treated as an ordinary line on the number 40 of that line being dialled in the first instance by the subscriber. This is a convenience when say at night the P. B. X. is unattended and incoming calls are passed through to a certain extension.
- If the number of any line of the P. B. X. group excepting the first line of the group as regards each level is dialled by the subscriber relay PR is short circuited across the wipers 10 and 11 and contact pr^3 so that it 45 cannot operate and the operations occurring on testing the line are the same as in the case of a call to an ordinary line.
- Winding 1 of relay PS is connected to an eleventh contact in the test bank and 50 when the test wiper leaves the tenth test contact on finding the associated P. B. X. line busy, relay T and relay PS energizes on reaching the eleventh contact. Relay T at its contact opens the circuit of relay PR and the latter by its release opens the rotary magnet circuit at contact pr^2 . The release 55 of relay PR also results in the opening of the holding circuit of relay G at contact pr^1 and relay G releases.
- Relay PS being energized contact ps^1 is 60 changed over and relay PT is energized in series with winding 2 of relay PS in the following circuit:—earth, battery, closed contact n^4 , winding of relay PT, winding 2 of relay PS, front contact ps^1 , rotary off-normal contact w^2 , closed contact g^1 , earth. Relay PT energizes and at contact pt^4 opens the circuit of relay T and the initiating circuit of relay PS. On relay T falling back 65 the circuit of the rotary release magnet M^1 is closed, the circuit being from earth over battery, back contact t^1 , contact ps^2 (closed when relay PS energized) magnet winding M^1 to earth.
- The wipers now return to the position 70 they originally reached when the wiper spindle was stepped up by the vertical magnet. The spindle rotary off-normal contact w^2 is restored to its normal position and breaks the circuit of relays PS and PT, but 75 relay PT is held over its contact pt^1 , contact w^2 and contact g^1 .
- Relay PS releases slowly and since contact w^1 is now closed relay D is meanwhile 80 energized in a circuit from earth over battery, closed contact n^4 , winding of relay D, front contact pt^3 , front contact ps^3 of relay PS, contact k^3 in its off-normal position, contact w^1 to earth. Relay D energizes and 85 since the circuit of relay A was previously broken at contact pt^2 , the circuit of the vertical magnet H is closed over contact d^2 of relay D, the circuit being ground over battery, front contact d^2 , back contact a^1 , back contact g^2 , magnet H, to earth, and the 90 wipers are stepped up opposite the next level. Relay D releases slowly on the opening of contact ps^3 .
- A circuit is now available for the energization 95 of relay G being as follows:—earth, battery, contact n^4 , winding of G, back contact ps^4 , back contact d^1 , back contact ps^3 , off-normal contact k^3 , closed contact w^1 to earth. Relay G on energization prepares the 100 circuit of the rotary magnet R at g^2 , and by the closure of contact g^4 causes the energization of relay D in a circuit from earth over battery, contact n^4 , winding of relay D, front contact pt^3 , contact g^4 , contact w^1 to earth.
- The rotary magnet circuit is completed 105 at contact d^2 and the wipers are given one step whereupon the circuit of relay D is broken at w^1 . Meanwhile the holding circuit of relay PT has been opened at contact g^1 , and on the slow fall back of relay PT 110 being complete, relay A is re-energized over contact pt^2 . Relay A opens the existing circuit of the rotary magnet R at contact a^1 and connects the rotary magnet over front contact a^1 to front contact pr^2 .
- Operations now proceed in a manner before described. If the line on which the wipers rest is free, relay T responds and the called line is rung. If the line is busy, 115 relay PR energizes and the rotary magnet 120
- 125
- 130

is operated over the circuit including contact pr^2 . It will be seen that PS initiates the release of the wipers and the stepping up to the next level. If the group of P. B. X. lines covers only two levels the wipers after now hunting unsuccessfully over the level do not encounter a circuit to a relay PS on the eleventh contact and there any suitable arrangement may be provided for giving a busy signal.

It should also be noted that a relay PS need not necessarily be connected to the eleventh contact, but may be connected to the test contact succeeding the test contact of the last line of the P. B. X. lines situated in that level.

Fig. 2 shows a case of a group selector arranged for successive hunting over two or more levels.

Referring to Fig. 2 on the seizure of the group selector, impulse relay A energizes in a circuit from earth, over contact ps^3 of relay PS, the winding of relay A, back contact t^3 of relay T, the B lead to battery at the preceding switch.

Relay A energizes and at contact a^2 closes a circuit for slow release relay D as follows—earth, battery, winding of relay D, vertical off-normal contact k^3 , front contact a^2 , the C lead to earth at the preceding switch.

Relay D at contact d^2 prepares a circuit for the vertical magnet H. On the first impulse being received, relay A releases and over its back contact a^1 closes the circuit of the vertical magnet H, the circuit being from earth over contact t^5 of relay T, front contact d^2 , contact a^1 , the vertical magnet H to earthed battery. The wipers are given one vertical step whereupon the off-normal k contacts operate. By the change-over of contact k^3 , relay D is held during the train of impulses over contact k^3 , front contact d^1 and back contact a^2 of relay A. Battery over resistance and contact k^1 is also disconnected on the first vertical step, from the incoming test lead; this effects no change as the test relay of the preceding switch is assumed to be held in a local circuit and to apply earth to the C wiper of that switch.

At the end of the train of impulses, relay A is held energized and the holding circuit of relay D is broken at back contact a^2 . Relay D releases, and at its back contact d^2 closes the circuit of the rotary magnet, the circuit being from earth, over battery, interrupter 18, rotary magnet R, front contact a^3 , closed contact k^2 , back contact d^2 , contact t^5 to earth. The wipers are stepped round in search of a free link, and on reaching the same, relay T energizes in a circuit from battery at the succeeding switch, the incoming test lead, bank contact and C wiper of the group selector, winding 2 of relay T, front contact a^2 of relay A, the C

lead to earth at the preceding switch. Engaged links have earths on their C bank contacts, relay T energizing closes a locking circuit for itself over contact t^1 , the circuit being from earth over battery, contact pt^2 , winding 1 of relay T to the C lead. At contact t^1 earth is applied to the C wiper to mark the link engaged. At front contacts t^2 and t^3 the A and B leads are connected through to the wipers; at contact t^5 the circuit of the rotary magnet is broken. Relay A has its circuit broken at back contact t^3 and releases disconnecting winding 2 of relay T from the C lead.

If however all the ten links in the level are engaged the wipers are stepped onto the eleventh bank contacts. A circuit is then made as follows, earth, over battery, contact pt^1 , winding 2 of relay PS, the eleventh bank contact, the C wiper, winding 2 of relay T, front contact a^2 to the earthed C lead. Relays T and PS operate. Relay T energized, connects its winding 1 to the incoming C line over contact t^1 , at contact t^5 the circuit of the rotary magnet is broken. Relay A is also disconnected at back contact t^3 . Relay PS by closing contact ps^1 makes the following circuit: earth over battery, back contact d^3 , winding 1 of relay PS, winding of relay PT, front contact ps^1 to earth. At contact ps^2 the circuit of the main release magnet is opened and at contact ps^3 another point in the circuit of relay A is opened.

When relay PT operates a circuit for relay D is prepared over contact pt^2 . At contact pt^3 the circuit of the holding winding 1 of relay T is opened and at contact pt^1 the circuit of operating winding 2 of relay PS and operating winding 2 of relay T is opened. Relay T releases and contact t^5 falling back, the circuit of the rotary release magnet M^1 is now made from earth over contact t^5 , back contact d^2 , contact pt^4 , rotary off-normal contact w^2 , rotary release magnet M^1 to battery.

The selector then releases as regards rotary movement. When the wipers have returned to the position they occupy before rotary movement, the off-normal contacts w are back at normal. The closure of contact w^1 results in the energization of relay D in a circuit from earth over battery, winding of relay D, contact k^3 in the off-normal position, contact w^1 , front contact pt^2 to earth. Relay D operates and is held over contact d^1 , back contact a^2 and the C line. At contact d^2 the circuit of the vertical magnet H is made and the wipers are consequently raised one step to the next level. At contact d^3 the circuit of relays PS and PT is opened and these relays release. Contact ps^3 falls back and the circuit of relay A is made, relay T having previously fallen back. The change-over of contact a^2

causes the release of relay D. The selector rotary magnet now receives current in a circuit from earthed battery over interrupter 18, rotary magnet, front contact a^3 , contact k^2 , back contact d^2 , contact t^5 to earth and the selector wipers now search for a free link.

If the group of lines covers more than two levels relay PS is connected to the 10 eleventh contact of each level with the exception of the last. The eleventh contact of the last level may be connected to battery so that relay T operates and stops the wipers on the eleventh contacts. A busy tone circuit connected to eleventh A and B bank contacts could then give a busy signal to the calling subscriber.

What I claim as my invention and desire to secure by Letters Patent is:—
20 1. In a telephone system a selector having two directional motion, wipers which execute a first movement and a second movement, means for causing release as regards the second movement on a predetermined contact being reached in that movement and for returning the wipers to the starting position for that movement and means automatically operating for re-starting the first movement on the return of the 25 wipers.

2. In a telephone system a selector having two directional movement, wipers which execute a vertical movement followed by a 30 rotary movement, means for causing release as regards the rotary movement on a predetermined contact being reached in that movement and for returning the wipers to the starting position for that movement and means automatically operating for re-starting the vertical movement on the return of the 35 wipers.

3. In a telephone system a selector having two directional motion, wipers which execute a vertical movement followed by a 40 rotary movement, a rotary release magnet, means for operating said magnet on a predetermined contact being reached in the rotary movement and means automatically operating for re-starting the vertical movement on the return of the wipers to the 45 starting position for the rotary movement.

4. In a telephone system a selector having two directional motion, wipers which execute a first movement and a second movement, means for stopping the second movement on a predetermined contact being reached in that movement, means for then causing release as regards the second movement and the return of the wipers to the starting position for that movement and means automatically operating for restarting the first movement on the return of the 50 wipers.

5. In a telephone system a selector having two directional motion, wipers which exe-

cute a first movement and a second movement, a relay which on the wipers reaching a predetermined contact in the second movement causes a cessation of the second movement, means for then causing release 70 as regards the second movement and for returning the wipers to the starting position for that movement and means automatically operating for re-starting the first movement on the return of the said wipers.

6. In a telephone system a selector having two directional motion, wipers which execute a first movement and a second movement, a first relay which on the wipers reaching a predetermined contact in the second movement causes a cessation of the second movement, means for then causing release as regards the second movement and for returning the wipers to the starting position for that movement, a second relay 80 which controls the circuit of the first relay and means automatically operating for re-starting the first movement on the return of the wipers.

7. In a telephone system a selector having two directional motion, wipers which execute a first movement and a second movement, a release controlling device for causing release as regards the second movement, means for stopping the second movement of the wipers on reaching a predetermined contact in that movement, a relay controlling the circuit of said release controlling device, means for causing the operation of said relay on said predetermined contact being reached and means automatically operating for restarting the first movement on the return of said wipers to the starting position for the second movement.

8. In a telephone system a selector having two directional motion, wipers which execute a first movement and a second movement, a release device for causing release as regards the second movement, means for stopping the second movement of the wipers on reaching a predetermined contact in that movement, a relay exercising control over the operation of the said release controlling device which relay operates on said predetermined contact being reached, a further relay controlled by said relay said further relay controlling the means for stopping the second movement of the wipers and means automatically operating for re-starting the first movement on the return of the wipers to the starting position for the second movement.

9. In a telephone system a selector having two directional movement, wipers, means for causing a first movement of the said wipers, means for causing a second movement of the said wipers, a release controlling device for causing release as regards the second movement, means for causing the operation of said release controlling device 125

on a predetermined contact being reached in that movement and means automatically operating for temporarily bringing into action the means causing the first movement 5 of the said wipers after the return of the wipers to the starting position for the second movement.

10. In a telephone system a selector having two directional motion, wipers, means for causing a first movement of the said wipers, means for causing a second movement of said wipers, a release controlling device for causing release as regards the second movement, means for causing the operation of said release controlling device on a predetermined contact being reached in the second movement, means automatically operating for temporarily closing the circuit energizing the means causing the first 20 movement of the wipers on the return of the wipers to the starting position for the second movement, and shaft contacts controlling the means for temporarily closing the circuit.

25. 11. In a telephone system a selector having two directional motion wipers, means for causing a first movement of the said wipers, means for causing a second movement of said wipers, a release controlling device for causing release as regards the second movement, means for causing the operation of the said release controlling device on a predetermined contact being reached in the second movement and means 30 for temporarily closing the circuit energizing the means causing the first movement comprising a slow release relay controlling said means and shaft contacts opening the circuit of the said slow release relay on the return of the wipers after reaching the said predetermined contact.

12. In a telephone system a selector having two directional motion, wipers, means for causing a first movement of the said wipers, a release controlling device for causing release as regards the second movement, means for causing the operation of the said release controlling device on a predetermined contact being reached in the second movement and means for temporarily closing the circuit energizing the means causing the first movement comprising a relay controlling the circuit of the said means, a second relay for preparing a circuit for said 45 relay, a slow release relay for further preparing a circuit for said first relay, shaft contacts for opening the circuit of the said slow release relay and for closing the circuit of the first relay, said shaft contacts 50 operating on the return of the wipers after reaching the said predetermined contacts.

13. In a telephone system a selector having two directional motion, wipers, a magnet for causing a first movement of the said wipers, a magnet for causing a second move-

ment of the said wipers, a release magnet for causing release as regards the second movement, a test relay for stopping the second movement on reaching a predetermined contact in that movement, a second relay energized on the wipers reaching said predetermined contact and which exercises control on the circuit of the said release magnet, a third relay for opening the circuit of said test relay and means for temporarily closing the circuit of the magnet causing the first movement after the wipers have returned, said means comprising a relay controlling the circuit of said magnet, the said third relay, and shaft contacts.

14. In a telephone system a selector having two directional motion, wipers which execute a first movement and a second movement, a release controlling device for causing release as regards the second movement, means for causing the operation of said release controlling device on the wipers reaching a predetermined contact in the second movement, means for restarting the first movement on the return of the wipers and means for subsequently starting the second movement.

15. In a telephone system a selector having two directional motion, wipers which execute a vertical movement and a rotary movement a release controlling device for causing release as regards rotary movement means for causing the operation of said release controlling device on the wipers reaching a predetermined contact in the rotary movement, means for re-starting the vertical movement on the return of the wipers and means for subsequently starting the rotary movement.

16. In a telephone system a selector having two directional motion wipers which execute a vertical movement and a rotary movement, a release controlling device for causing release as regards rotary movement, means for operating said release controlling device on reaching a predetermined contact in the rotary movement, means for causing a vertical movement of the wipers on their return, means for preparing a circuit for energizing the means causing rotary movement of the wipers and means for completing said circuit.

17. In a telephone system a selector having two directional motion, wipers which execute a vertical movement and a rotary movement, a release controlling device for causing release as regards rotary movement, means for operating said release controlling device on reaching a predetermined contact in the rotary movement, means for causing a vertical movement of the wipers on their return, a slow release relay, a second relay the circuit of which is closed on the release of the said slow release relay said second relay preparing a circuit for energizing the

means causing rotary motion of the wipers.

18. In a telephone system a selector having two directional motion, wipers which execute a vertical movement and a rotary movement, a release controlling device for causing release as regards rotary movement means for operating said release controlling device on reaching a predetermined contact in the rotary movement, means for causing 10 a vertical movement of the wipers on their return, a slow release relay, a second relay the circuit of which is closed on the release of the said slow release relay, said second relay preparing a circuit for energizing the 15 means causing the rotary movement of the wipers, a third relay for completing said circuit and means for temporarily energizing said third relay.

19. In a telephone system a selector having two directional motion wipers which execute a vertical movement followed by a rotary movement, a release controlling device for causing release as regards rotary movement, a test relay for stopping the 25 rotary movement of the wipers on reaching a predetermined contact in that movement a slow release relay for controlling the circuit of the said test relay, means for causing the operation of the release controlling 30 device on the predetermined contact being reached, means for causing a vertical movement of the wipers on the return of the wipers, a second slow release relay, a further relay the circuit of which is closed on the 35 release of the first slow release relay said further relay preparing a circuit for energizing the means for causing rotary movement of the wipers, a third relay for completing the circuit for energizing the said 40 means an energizing circuit for said third relay controlled by the first slow release relay and said further relay.

20. In a telephone system a selector having two directional movement, wipers which execute a first movement and a second movement, means for causing said movements, an impulse relay controlling over a contact 45 thereof a circuit for energizing the means

for causing said movements, means for causing the release as regards the second movement of the wipers on reaching a predetermined contact in that movement means for thereon causing the de-energization of said impulse relay means for temporarily closing a circuit for energizing the means for causing a first movement of the wipers and means for subsequently closing a circuit for energizing the means for causing a second movement of the wipers.

21. In a telephone system a selector having two directional motion, wipers which execute a first movement and a second movement, means for causing said movements an impulse relay controlling over a contact thereof a circuit for energizing the means 60 for causing said movements first and second slow release relays controlling release as regards the second movement when a predetermined contact is reached in that movement, means controlled by the first slow release relay for temporarily energizing on the return of the wipers the means causing the first movement, a further relay and means controlled by said further relay for energizing the means causing the second 65 movement of the wipers.

22. In a telephone system a selector having two directional motion, wipers which execute a first movement and a second movement, means for causing said movements, an 80 impulse relay controlling over a contact thereof a circuit for energizing the means for causing said movements first and second slow release relays controlling release as regards the second movement when a predetermined contact is reached in that movement, means controlled by the first and second slow release relays for temporarily energizing on the return of the wipers, the means causing the first movement of the 85 wipers, a further relay and means controlled by said further relay and the second slow release relay for energizing the means causing the second movement of the wipers.

In testimony whereof I affix my signature.
DAVID ADAM CHRISTIAN.
